FIG.1

FIG.2

FIG.3

FIG.4

FIG. 5

FIG. 6

FIGURE 1 is a top plan view of a playing card box, showing my new design; and

FIGURE 2 is a side elevational view thereof; and

FIGURE 3 is a side elevational view similar to FIGURE 2 but with the cover in open position; and

FIGURE 4 is an end elevational view thereof; and

FIGURE 5 is a perspective view of the box with the cover in closed position; and

FIGURE 6 is a perspective view of the box with the cover in open position.

The side and end of the box opposite to those illustrated in FIGURES 2, 3 and 4 are exactly the same as shown in the respective figures. The dominant feature of my design resides in the two cover members wherein

the top surfaces thereof are shallowly recessed near the box ends and taper upwardly toward the center of the box along lines substantially parallel to the top edges of the box body, and taper upwardly and outwardly toward the box sides and ends as shown.

I claim:

The ornamental design for a playing card box, as shown and described.
